Atty's.

UNITED STATES PATENT OFFICE.

FRED E. WHITE, OF GARDNER, MASSACHUSETTS, ASSIGNOR TO CENTRAL OIL & GAS STOVE COMPANY, OF GARDNER, MASSACHUSETTS, A CORPORATION OF MASSACHUSETTS.

AIR-DISTRIBUTER FOR OIL-STOVES.

1,354,083.

Specification of Letters Patent. Patented Sept. 28, 1920.

Application filed September 11, 1919. Serial No. 323,060.

To all whom it may concern:

Be it known that I, FRED E. WHITE, a citizen of the United States, and resident of Gardner, Massachusetts, have invented 5 certain new and useful Improvements in Air-Distributers for Oil-Stoves, of which the following is a specification.

My present invention relates to improvements in air distributers for oil stoves and 10 aims to provide a construction which will provide a better supply and distribution of the air to the flame, in which liability of impairment of the operation of the burner will be reduced to a minimum, and also to 15 secure a device which may be manufactured at a minimum cost.

The invention includes the novel features of construction and arrangement and combination of parts hereinafter described and 20 defined by the appended claims.

Embodiments of the invention are illustrated in the accompanying drawing in which:—

Figure 1 is a central vertical section 25 through the distributer associated with a burner.

Fig. 2 is a detail sectional view on line 2—2 of Fig. 1.

Fig. 3 is a view of a modification.

Referring by reference characters to this 30 drawing the inner wick tube is shown at 1, the outer wick at 1^a and the wick at 2. These parts may be of the ordinary or any 35 desired construction such as shown for example in Letters Patent of the United States granted October 22, 1918, No. 1,282,663.

3 designates my improved air distributer 40 as a whole which is provided with an annular horizontal shoulder 3^a designed to overlie the upper edge of the wick and serve as a wick stop, the distributer having an 45 annular depending flange or portion 3^b adapted to telescope within the inner wick tube.

Immediately below the shoulder 3^a the flange is preferably inclined inwardly or 50 slightly contracted and provided with an annularly arranged perforations as indicated at 3^c. From the outer edge of the shoulder 3^a the distributer is extended substantially vertically to provide an annular perforated wall 3^d, the upper end of which is con-

tinued upward in substantially frusto-conical form as indicated at 3^e, which portion is 55 likewise perforated as shown.

At the upper end of this frusto-conical portion the metal is turned inward into a horizontal plane as indicated at 3^f to form a seat for the distributer head, and this 60 portion 3^f is also preferably perforated at π as illustrated in the drawing.

The distributer head comprises a disk shaped portion 4 having an open center and an outer substantially vertical annular wall 65 4^a suitably perforated, the latter having preferably an outwardly turned flange or rim 4^b to which the closing cap 5 of the distributer head is connected, preferably by spinning.

The lower wall or bottom 4 of the distributer head is held spaced from the portion 3^f to provide an open annular air channel, and a convenient and economical manner of so holding it is to provide one of the 75 walls (as for example 4) with a plurality of annularly arranged projections 4^c which bear against the other wall, the parts being secured together by spinning the edges of the alining openings, the one over the other, as 80 shown at γ . The perforations in the portion 3^f are preferably made larger than in the frusto-conical wall to prevent liability of their becoming clogged, while at the same time the walls being parallel to each other 85 and the annular space there-between entirely open except for the space occupied by the projections 4^c, permits the walls to be located in comparatively close proximity and yet secures a substantial flow of air at 90 reduced velocity. The bottom 4 of the distributer is preferably inclined downwardly and outwardly which imparts a downward deflection to the film of air.

The locking skirt for holding the distributer in place within the wick tube is 95 shown at 6. The distributer parts are customarily made of brass. The skirt I prefer to make of sheet steel in the form of a cylinder having the projecting locking tongues 100 6^a designed, after the distributer is seated, to be moved into locking engagement with the locking bar 8 by rotary movement as described in the patent aforesaid.

To secure the skirt to the depending 105 sleeve or flange of the distributer, I provide

one of the parts as for instance the sleeve with openings 6^b and punch the metal of the other part into these openings.

Instead of joining the edges of the parts 5 4 and 3^c as shown in Fig. 1 and relying on said latter member to admit air to the channel I may leave said channel open at its inner periphery as shown in Fig. 3, the connection between the parts 4 and 3^c being 10 made at intervals as illustrated in said figure at y'.

Having thus described my invention, what I claim is:

1. An air distributor for wick stoves having an annular perforated wall and a substantially horizontal annular perforated portion at its upper part, and a distributor cap held above and spaced from said horizontal portion and providing an air distributing space between itself and said horizontal portion.

2. An air distributor for wick stoves having an annular wall and a substantially horizontal annular portion at its upper part, 25 and a distributor cap held above and spaced from said horizontal portion to provide an air distributing space between itself and said horizontal portion, said cap having an imperforate bottom wall projecting laterally 30 beyond the said annular wall.

3. An air distributor for wick stoves having an annular perforated wall and a substantially horizontal annular portion at its upper part, and a distributor cap having a 35 downwardly and outwardly inclining imperforate bottom wall held above and spaced from said horizontal portion to form an air distributing space, substantially as described.

40 4. An air distributor for wick stoves having an annular perforated wall and a substantially horizontal top portion provided with annularly arranged perforations and

an open center, and a burner cap having a bottom wall provided with an open center, 45 one of said walls having projections contacting with the other wall to hold them spaced apart, and said parts being united at the edges of their open centers.

5. An air distributor for wick stoves having a frusto-conical upper perforated portion terminating in an inwardly extending horizontal portion at its smaller upper end, and a cap having its bottom arranged above and spaced apart from the said horizontal portion with means for the passage of air to the space between said bottom and the horizontal portion, the bottom of said distributor overhanging the wall of the frusto-conical part, substantially as described. 50

6. An air distributor for wick stoves having a frusto-conical upper perforated portion terminating in an inwardly extending horizontal portion at its smaller upper end, and a cap having its bottom arranged above 65 and spaced apart from the said horizontal portion with means for the passage of air to the space between said bottom and the horizontal portion, the bottom of said distributor overhanging the wall of the frusto-conical part, and inclining downwardly and 70 outwardly, substantially as described.

7. An air distributor for wick stoves having a frusto-conical perforated portion with an inwardly extending horizontal portion at 75 the top, an inwardly extending horizontal portion connected with the frusto-conical portion and forming a wick stop, a cap supported by and spaced apart from the upper horizontal portion to form an air passage 80 between its bottom and the upper horizontal portion, said bottom overhanging the frusto-conical portion, substantially as described.

In testimony whereof I affix my signature. 85
FRED E. WHITE.
